UNITED STATES PATENT OFFICE

CORNELIUS G. BOUDETTE, OF CLAREMONT, NEW HAMPSHIRE, ASSIGNOR TO SULLIVAN MACHINERY COMPANY, A CORPORATION OF MASSACHUSETTS

MINING MACHINE

Application filed October 31, 1927. Serial No. 230,004.

This invention relates to mining machines and more particularly, but not exclusively, pertains to coal mining machines of the wheel mounted "universal" type adapted to operate 5 from the mine trackway.

An object of this invention is to provide an improved coal mining machine of the wheel mounted type. Another object is to provide an improved coal mining machine adapted 10 to operate either as a horizontal cutter or a shear cutter. Still another object is to provide a coal mining machine having improved elevating and tilting mechanism for the cutting mechanism and improved mechanism 15 for rotating the cutter carrying head to change the plane of operation of the cutter bar. Yet another object is to provide an improved coal mining machine of the combined horizontal and shear cutter type wherein the 20 cutter bar may be expeditiously adjusted into a plurality of operative positions. A still further object is to provide an improved coal mining machine of the wheel mounted type having improved elevating and tilting mechanism 25 for the machine body whereby the elevation and angle of the cutter bar may be varied to suit different cutting conditions. These and other objects and advantages of this invention will, however, hereinafter 30 more fully appear.

In the accompanying drawings there is shown for purposes of illustration one form which the invention may assume in practice.

In these drawings,—

Fig. 1 is a plan view of a mining machine constructed in accordance with an illustrative embodiment of the invention.

Fig. 2 is a side elevational view of the machine shown in Fig. 1, the machine being 40 shown in its elevated position.

Fig. 3 is an enlarged fragmentary plan view of the machine shown in Fig. 1, parts being shown in section to illustrate details of construction.

Fig. 4 is a transverse vertical sectional view taken on line 4—4 of Fig. 3.

Fig. 5 is a vertical detail sectional view taken on line 5—5 of Fig. 4.

Fig. 6 is a detail view illustrating the con-

trolling arrangement for the clutches and brake bands.

Fig. 7 is an enlarged vertical longitudinally extending sectional view taken on line 7—7 of Fig. 3 and illustrating the plural 55 speed transmission mechanism.

Fig. 8 is a transverse vertical detail sectional view taken on line 8—8 of Fig. 7.

Fig. 9 is a transverse vertical sectional view taken on line 9—9 of Fig. 2.

Fig. 10 is a transverse vertical sectional view taken on line 10—10 of Fig. 2.

Fig. 11 is a diagrammatic view illustrating the improved elevating and tilting mechanism, the mechanism being shown in a plurality of positions as indicated by dotted lines.

In this illustrative embodiment of the invention there is shown a coal mining machine of the so-called "universal" type mounted 70 on wheels and operating from the mine trackway. The machine is of the same general type as those described in the co-pending applications of Morris P. Holmes, Ser. No. 6,477, filed Feb. 2, 1925 and Ser. No. 137,600, filed September 24, 1926 and generally comprises a machine body 1 composed of a section 2 housing the driving connections for the cutting mechanism, a motor section 3 and a section 4 housing the plural speed trans-

mission means for the truck drive, for rotating the cutter carrying head, and for elevating and tilting the machine body, these sections 2, 3 and 4 being rigidly united and suitably mounted on a wheel mounted frame 80 generally designated 5. As illustrated, the wheel mounted frame 5 includes longitudinally spaced transverse frames 6 and 7 held in rigid spaced relation by parallel longitudinally extending frames or angle members 8,

the latter being secured to the transverse frame members by suitable screws 9. As clearly shown in Figs. 9 and 10 the transverse frame members 6 and 7 are respectively 85 provided with semicircular bores 10, while 90 pivotally connected to these frame members as at 11 are pivoted cap members 12, each held in position by suitable clamping screws 13. The semi-circular bores 10 and cap mem-

bers 12 receive split bearing sleeves 14 in 95 100

which cylindrical portions 15 formed on frame sections 16 and 17 are respectively rotatably mounted, the frame sections 16 and 17 being connected as by bolts 18 (see Fig. 3) 5 respectively to the opposite ends of the motor section 3, the frame sections 2 and 4 also being rigidly connected to the frame sections 16 and 17, respectively. It will be noted that the frame sections 2, 3, 4, 16 and 17 when 10 united form the body 1 of the machine and this body is rotatably mounted within the bearings 14 for rotation about its longitudinal axis relative to the wheel mounted frame 5 as will later be described. As illustrated, 15 suitably connected to the transverse frame members 6 and 7 are pivoted supporting arms 19 and 20 which carry the truck wheels 21, the arms 19 and 20 and the wheels 21 constituting the supporting means for the machine. 20 In specifically describing the plural speed transmission mechanism housed within the frame section 4 it will herein be noted that housed within the motor section 3 is a suitable driving motor 25 herein preferably of the usual reversible electric type having a horizontal armature shaft 26 extending longitudinally of the machine. The rear end of the armature shaft 26 has suitably secured 25 thereto a coupling member 27 (see Fig. 3) clutched at 28 to a shaft 29 disposed in longitudinal alinement with the armature shaft. The rear end of the shaft 29 has suitably fixed 30 thereto a spur pinion 30 which is adapted to 35 drive the truck wheels, the elevating and tilting mechanism, and the rotating mechanism for the cutter carrying head through transmission mechanism to be hereinafter described including transmission gearing and 40 controlling clutches, substantially similar to those described in a copending application of Morris P. Holmes, Ser. No. 757,031, filed December 18, 1924, at a slow speed in one direction or at a fast speed in the reverse direction 45 without reversing the motor. In specifically considering the fast speed transmission it will be noted that the pinion 30 (see Fig. 7) meshes with a spur gear 31 and this gear 31 has secured thereto and rotatable 50 therewith a spur pinion 32 which in turn meshes with a large internal gear 33. The hub 34 of the gear 33 is herein journaled on a suitable bearing sleeve 35 on a sleeve clutch member 36 keyed as at 37 to a longitudinally 55 disposed horizontal main driving or transmission shaft 38 suitably journaled within the frame section 4. Moreover, it will be noted that the member 36 carries a series of friction clutch discs 39, which discs cooperate with a corresponding series of clutch discs 40 carried by the sleeve of the internal gear 33. As shown, the sleeve on the internal gear is also provided with a plurality of radially located longitudinally extending slots 60 65 41 receiving radial fingers 42 on an inter-

locking member 43 keyed to the hub of a spur pinion 44 freely rotatable on the shaft 38. Projecting between these fingers 42 are friction clutch operating fingers 45 carried by a cylindrical plane member 46 disposed coaxially with the hub of the gear 44. These fingers 45 extend longitudinally into contact with the end disc of one set of friction discs 39 and 40. Herein, as shown, the rear end of the shaft 38 has secured thereto by a key 47, a spur pinion 48 which meshes with a spur gear 49. The spur gear 49 has secured thereto and rotatable therewith a spur pinion 50 which meshes with a large internal gear 51 keyed as at 52 to a longitudinally extending 70 horizontal transmission shaft 53 disposed in longitudinal alinement with the shaft 38. It will thus be noted that rotation of the armature shaft 26 may be transmitted to the pinion 30, gear 31, pinion 32, internal gear 33, friction clutch discs 39, 40, clutch member 36, shaft 38, pinion 48, gear 49 pinion 50, internal gear 51 and the shaft 53 to rotate the latter at a predetermined high speed or fast speed whenever the clutch controlling member 46 is operated to apply the clutch. It will here further be evident that this speed may be lowered at will by slipping the friction discs 39, 40. 75 Referring to the slow speed transmission it will be noted that when the clutch controlling member 46 is in inoperative position and the clutch is released, power will still be transmitted through the interlocking member 43 to the pinion 44 which is freely rotatable on the shaft 38. This pinion in turn meshes with a spur gear 54 disposed coaxially with the gear 31 and this gear has secured thereto and rotatable therewith a spur pinion 55 which meshes with a spur gear 56 rotatably 80 mounted on the shaft 38. The gear 56 has secured thereto and rotatable therewith a spur pinion 57 which meshes with a spur gear 58 disposed coaxially with the spur gear 54 and this gear drives a spur pinion 59 which meshes with an internal gear 60 substantially 85 similar to the internal gear 33. The internal gear 60 also houses a friction clutch substantially similar to the clutch heretofore described in connection with the clutch discs 39 and 40 and this clutch includes friction clutch discs 61 and 62, certain of which are carried on a clutch member 63 keyed at 64 to the shaft 38, while others are carried by a sleeve formed on the internal gear 60. A clutch retaining member 65 is provided, keyed at 66 to the hub of the spur pinion 48 and this clutch member in this instance has no interlocking function and functions only as a disc retaining member. A cylindrical plane 90 clutch operating member 67 surrounds the hub of the clutch member 65 and is provided with longitudinally extending fingers 68 which are adapted to engage the end disc of one set of the friction discs 61, 62. As a re- 95

sult of this mechanism above described, although the clutch 39, 40 is disconnected, rotation will constantly be imparted through the pinion 44, gear 54, pinion 55, gear 56, pinion 57, gear 58, pinion 59, and internal gear 60, clutch discs 61, 62, clutch member 63, pinion 48, gear 49, pinion 50, internal gear 51 and to the shaft 53 so that when the clutch 61, 62 is connected the shaft 53 will be rotated at a slow speed in an opposite or reverse direction from the fast speed previously described. Here it will also be evident that by slipping the friction discs 61, 62 this speed may also be reduced when desired.

15 Operatively associated with the clutches of the transmission mechanism above described are pivoted clutch shipper members 69 and 70 (see Figs. 3 and 8) provided at one end with suitable rollers 71 adapted to engage the 20 plane surfaces of the clutch operating members 46 and 67, respectively. The outer ends of these shippers are also provided with rectangular portions 72 and 72^a having arcuate engaging surfaces and these rectangular portions 25 are operatively connected to slidably engageable parallel rods 73 and 73^a, respectively (see Fig. 8) suitably guided within the machine frame at their opposite ends. These rods are provided at their rearward ends with 30 semi-circular portions having threads of opposite pitch and these threads engage a two-part nut 74 (see Fig. 3), each part having threads of opposite pitch which engage the threads on the rods 73 and 73^a. The nut 74 35 has suitably secured thereto a spur pinion 75 which is meshed with an internal gear 76 formed in a hand wheel 77 rotatably mounted at 78 upon a frame section 79 rigidly secured to the frame section 4. As this operating 40 mechanism for the clutches is clearly described in the copending application Ser. No. 6,477 mentioned above, further description herein is submitted to be unnecessary. It will be observed that rotation of the hand wheel 45 77 and consequently the threaded nut 74 engaging the threads formed on the rods 73 and 73^a will cause the latter to simultaneously move in opposite directions, thus causing one of the friction clutches to be released 50 while the other is applied, thereby preventing simultaneous application of both clutches.

The improved driving connections for the 55 tilting and elevating mechanism and the truck wheel driving mechanism as shown in the drawings specifically comprise a bevel gear 80, keyed at 81 to the rear end of the shaft 53. As illustrated, the bevel gear 80 meshes with reverse bevels 82 and 83 freely 60 rotatable upon bearing sleeves 84 carried by the hubs of a central two-part spider member 85, the latter in turn being rotatably mounted on bearing sleeves 86. The hubs of the bevel gears 82 and 83 carry a series of clutch discs 87 and 88, respectively, which

are interleaved with a corresponding series of clutch discs 89 and 90, respectively, carried by the hub portions of the spider member 85 arranged coaxially with the gears 82 and 83. At the remote sides thereof are clutch 70 applying members 91 and 92 each having projecting fingers 93 extending through the bevel gears into engagement with the end discs of the clutch discs. Engaging the 75 clutch applying members 91 and 92, respectively, are shipper yokes 94 and 95 secured to horizontal shafts 96. Fixed to each of the shafts 96 is a depending arm 97 and these arms are connected together by a transverse operating rod 98 as clearly shown in Fig. 6. 80 Engaging the rod 98 and pivotally mounted on the exterior of a housing 99 is an operating lever 100. The housing 99 is suitably rigidly secured to the angle members 8 of the wheel mounted frame and carries a suitable bearing within which the rear end of the machine body 1 is rotatably mounted, this bearing being arranged coaxially with the motor axis. From the foregoing, it is evident 85 that when the lever 100 is swung in one direction one of the clutches is applied while the other is released, thereby enabling the bevel gears 82 and 83 to be alternatively connected in driving relation with the central spider 85. As clearly shown in Fig. 4 secured to the spider 85 are radially aligned stub shafts 101 having journaled thereon bevel gears 102 meshing with bevel gears 103 and 104, respectively, arranged coaxially with bevel gears 82 and 83 heretofore described. 90 These bevel gears 102, 103, and 104 constitute a differential. As illustrated, the bevel gear 103 is keyed at 106 to a sleeve 107 suitably journaled in ball bearings 108 carried by the housing 99. The bevel gear 104 is keyed at 105 110 to a similar sleeve 111. Keyed to the remote ends of the sleeves 107, 111, respectively, at 112 and 113 are brake drums 114 and 115 each having a peripheral groove 116 with which brake bands 117 and 118 cooperate respectively. It will herein be noted that disposed coaxially with and extending through the sleeves 107, 111 are aligned shafts 119 and 120 having their adjacent ends grooved or slotted at 121, and a transverse portion or bar 122 formed integral with the spider 85 engages these slots, thereby rigidly locking the shafts to the spider for rotation therewith. The outer ends of these shafts are journaled 120 in ball bearings 123 suitably carried within the housing 99. The brake drums 114, 115 have housed therein and connected thereto a series of clutch discs 124 and 125 respectively which are interleaved with a corresponding series of clutch discs 126 and 127 carried by clutch members 128 and 129, respectively, rotatably mounted on bearing sleeves 130 and supported by the shafts 119, 120, respectively. The clutch members 128, 129 are respectively 125 connected by clutch teeth 131 to worms 132 130

and 133 also rotatably mounted on the bearing sleeves 130.

In this instance, the worm 132 meshes with a worm gear 134 rotatably mounted in ball bearings 135 carried by the housing 99 (see Fig. 11). The worm gear 134 is internally threaded at 136 and constitutes a nut threadedly connected to an axially movable screw 137 extending longitudinally of the machine. As shown in Fig. 10, the screw 137 has formed thereon at its forward end a rectangular portion 138 slidably mounted in a rectangular groove or slot 139 formed within the transverse frame member 7, the rear end of this screw being suitably guided within the housing 99. The bottom portion of the rectangular portion of the screw 137 has formed thereon rack teeth 140 which mesh with teeth 141 formed on a gear segment 142. The gear segment 142 is suitably fixed to the rear machine supporting arm 20. Again referring to Fig. 4 it will be observed that the worm 133 meshes with a worm gear 143 similar to the worm 134 and likewise journaled within the housing 99. The worm gear 143 constitutes a nut member threadedly connected to an axially movable screw 144 disposed parallel with the screw 137 but at the opposite side of the machine. As shown in Fig. 9 the screw 144 has formed thereon at its forward end a rectangular portion 145 guided within a slot or groove 146 formed within the transverse frame member 6. The screw 144 has formed thereon rack teeth 147 which mesh with teeth 148 on an arcuate gear segment 149. The gear segment 149 is suitably rigidly secured to the machine supporting arm 19. As clearly shown in Figs. 9 and 10 the arms 19 and 20 are pivotally mounted within bearing sleeves 150 and 151 suitably carried by the transverse frame members 6 and 7, respectively, as clearly described in the said applications to Morris P. Holmes. Operatively associated with the friction clutches 124, 126 and 125, 127 respectively, are clutch applying members 152 and 153 with which shipper yokes 154, 155 cooperate. These shipper yokes are respectively connected through transversely extending operating rods 156 and 157 (see Fig. 6) to operating levers 158 and 159 pivotally mounted at 160 on a bracket rigidly bolted to the side of the adjacent angle member 8. It is therefore evident that the clutches 124, 126 and 125, 127 may be selectively or simultaneously applied or released at will. The improved truck wheel driving mechanism comprises a clutch member 161 keyed at 162 to the outer end of the shaft 120. The hub of the clutch member has rotatably mounted thereon a chain sprocket 163 having clutch teeth 164 formed thereon adapted to be connected by a shifttable clutch member 165 to teeth 166 formed on the clutch member 161. As illustrated, the chain sprocket 163 is connected through an endless chain connection

167 to a chain sprocket 168 keyed as at 169 to a horizontal transversely disposed shaft 170 disposed coaxially with the pivot for the machine supporting arm 20 and extending through the bearing portions of the latter. As shown in Fig. 10 the opposite end of the shaft 170 has fixed thereto at 171 a chain sprocket 172 connected through an endless chain connection 173 to a chain sprocket 174. The chain sprocket 174 is keyed at 175 to a horizontal shaft 176 arranged parallel with the shaft 170. The shaft 176 is arranged coaxially with the pivot for the machine supporting arm 19 and extends through the bearing portions of the latter as clearly shown in Fig. 9. As illustrated, the shafts 170 and 176 are each connected through a train of spur gears 177, 178, 179 to axles 180 and 181, respectively. These axles have fixed thereto the truck wheels 21. The shipper clutch member 165 is operated by a shipper yoke 182 pivotally mounted at 183 on the housing 99. This shipper yoke is connected by an actuating rod 184 and a cooperating operating lever 185 pivotally mounted on the bracket supporting the levers 158, 159. As shown in Fig. 4, the central spider member 85 is provided with a peripheral groove 187 with which a brake band 188 cooperates (see also Fig. 5). The brake band 188 is provided with a threaded operating rod 189 carrying a suitable hand wheel 190 conveniently located at the top of the housing 99. Similar hand wheels 191, 192 are provided for the brake bands 117 and 118 respectively. It will herein be noted that the shaft 170 has fixed thereto at 193 a brake drum 194 with which a brake band 195 cooperates, suitable operating mechanism being provided including a pull rod 196 and a cooperating operating lever 197 pivotally mounted on the side of the wheel mounted frame 5.

The cutter carrying section 2 has pivotally mounted thereon for angular movement relative thereto an elongated plane cutter bar 198 about the margin of which a cutter bit carrying cutter chain 199 is adapted to be circulated. As the mechanism for driving the cutter chain 199 and for swinging the bar about its pivot does not specifically enter into this invention, and as these connections are clearly described in the copending application Ser. No. 6,477 mentioned above, further description is herein submitted to be unnecessary.

The general mode of operation of the machine will now be briefly described. When it is desired to propel the machine about the mine along the trackway in the entry at a fast or transport speed, the operator grasps the lever 185 and shifts the clutch member 165 outwardly from the position shown in Fig. 4 thereby connecting the chain sprocket 163 to the shaft 120. The friction clutch 87, 89 is then applied connecting the bevel gear

82 to the spider 85. The driving motor 25 is then started and the fast speed clutch 39, 40 is applied, and as a result the truck wheels are driven at a fast speed. It is obvious that upon release of the clutch 87, 89 and application of the clutch 88, 90 the truck may be driven rearwardly along the trackway at a fast speed. When the working face of the coal is reached the fast speed clutch is then released. If an undercut is desired to be made the cutter bar is swung or slewed at a fast speed to the right of the entry. The cutter chain sprocket is then connected to the motor and the cutter chain 199 rapidly circulated about the cutter bar. The slow speed clutch 61, 62 is then applied, the bevel gear 83 connected to the spider 85 upon application of the clutch 88, 90 and the machine is then fed forwardly along the trackway at a slow speed and the bar dumped beneath the coal, the clutch 88, 90 thereafter being released. The cutter bar is then swung to the opposite side of the entry. The operator then applies the clutch 87, 89 and the machine is propelled rearwardly along the trackway at a slow speed and the cutter bar withdrawn from beneath the face. If it is desired to make a shear or vertical cut the operator manipulates the hand wheel 190, thereby applying the brake band 188 and as a result the spider member 85 is held against rotation. The operator then applies one or the other of the friction clutches 87, 89 and 88, 90 and as a result one or the other of the bevel gears 82, 83 is held against rotation. The slow speed clutch 61, 62 is then applied thereby causing rotation of the bevel gear 80, the latter reacting against the stationary bevel gear with which it meshes, and as a result, the machine body is bodily rotated within its bearings about its longitudinal axis and the bar swung into a vertical plane. The shearing operation is substantially the same as that described above in connection with the undercutting operation. If it is desired to vary the elevation of the bar and the machine body, one or the other of the clutches 87, 89 and 88, 90 is applied, thereby connecting one or the other of the bevel gears to the spider member 85 and upon application of the clutches 124, 126 and 125, 127 the screws 137, 144 are moved axially within their guides, thereby swinging the racks 142, 149 together with the arms 19 and 20 and consequently the machine frame is moved upwardly or downwardly to the elevation desired. If it is desired to tilt the bar one or the other of the brake bands 117 and 118 is applied, thereby resisting rotation of one or the other of the bevel gears 103, 104 of the differential and consequently speeding up the other bevel gear, and as a result one of the screws is moved axially at a faster speed than the other. This causes one of the racks to be swung at a speed faster than the other, and

as a result the machine is tilted in an obvious manner about a transverse axis. It is obvious that upon suitable application of the brake bands 117, 118 the speed of axial movement of the racks 142, 149 may be varied as desired, the differential automatically inversely proportioning the power delivered to these racks. These and other uses and advantages of this invention will be clearly apparent to those skilled in the art. It will be noted that, in distinction from the disclosures of the earlier filed Holmes' applications referred to herein, in which pivoted supporting arms are disclosed, there is herein true independence in the power adjustment of the arms, each being adjustable independently of the other, and this mutual independence characteristic of this invention is to be understood when reference is made to mechanism for independently adjusting the supports, in the appended claims.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a machine body, adjustable front and rear supports therefor including support wheels adapted to run along a mine trackway, cutting mechanism carried by said body, a motor carried by said body, and mechanism driven by said motor for adjusting said front support independently of said rear support, said cutting mechanism having a mounting on said body permitting swinging through substantially a semicircle irrespective of the positions of said arms for varying the elevation and angle of said machine body relative to the support wheels.

2. In a mining machine, a machine body, cutting mechanism carried thereby, a motor in said body, adjustable front and rear supports for said body, and mechanism driven by said motor for adjusting said supports including a differential operatively connected to each support.

3. In a mining machine, a machine body, cutting mechanism carried thereby, a motor in said body, adjustable front and rear supports for said body, and mechanism driven by said motor for adjusting said supports including a differential operatively connected to each support, said differential being adapted to automatically inversely proportion the power transmitted to said supports by said motor.

4. In a mining machine, a machine body, cutting mechanism carried thereby, a motor in said body, adjustable front and rear sup-

- same to vary the angle in altitude and elevation of said body.
17. In a mining machine, a machine body, cutting mechanism carried thereby and swingable about a pivot adjacent one end of said body, adjustable front and rear supports for said body including support wheels adapted to run along a mine trackway, a motor carried by said body, and mechanism driven by said motor for independently adjusting said supports to vary the angle in altitude of said body relative to said support wheels.
18. In a mining machine, a machine body, cutting mechanism carried thereby and swingable about a pivot adjacent one end of said body, adjustable front and rear supports for said body including support wheels adapted to run along a mine trackway, a motor carried by said body, mechanism driven by said motor for independently or simultaneously adjusting said supports to vary the angle in altitude and elevation of said body relative to said support wheels, and mechanism driven by said motor for driving the truck wheels irrespective of the adjusted position of said supports.
19. In a mining machine, supporting means, a frame mounted thereon, and means for varying the elevation of said frame on said supporting means including a plurality of arcuate toothed members, axially movable racks cooperating therewith, and means for simultaneously sliding said racks comprising a differential having corresponding elements operatively connected thereto.
20. In a mining machine, supporting means, a frame mounted thereon, and means for varying the elevation of said frame on said supporting means including a plurality of arcuate toothed members, axially movable racks cooperating therewith, and means for independently or simultaneously sliding said racks comprising a differential having corresponding elements operatively connected thereto.
21. In a mining machine, a wheeled support, a machine body rotatably mounted thereon about its longitudinal axis, a motor carried by said body, mechanism driven by said motor for changing the elevation of said machine body relative to the wheels of said support, and means driven by said motor for effecting rotation of said body including a driving element arranged coaxially with said motor axis, a cooperating element connected to said driving element and on which the latter is adapted to react, and means for holding said cooperating element stationary during body rotation or for releasing it at will.
22. In a mining machine, a wheeled support including pivoted arms, a body on said support, a motor carried by said body, and means for swinging said arms to vary the elevation of said body including reciprocable

shafts and mechanism for independently reciprocating said shafts including a differential operatively connected to both of the same and having corresponding elements connected to each shaft.

23. In a mining machine, a wheeled support including pivoted arms, a body on said support, a motor carried by said body, and means for independently swinging said arms to vary the angle of said body including reciprocable shafts and means for independently reciprocating said shafts including a differential operatively connected to both of the same and having corresponding elements connected to each shaft.

24. In a mining machine, a machine body, cutting mechanism carried thereby, a motor in said body, adjustable front and rear supports for said body, and mechanism driven by said motor for independently adjusting said supports including an orbitally movable element through which power is transmitted to effect adjustment of both supports.

25. In a mining machine, a machine body, cutting mechanism carried thereby, a motor in said body, adjustable front and rear supports for said body, and mechanism driven by said motor for independently adjusting said supports including an orbitally movable element through which power is transmitted to effect adjustment of both supports, and means for effecting rotation of said element in opposite directions to effect adjustment of said supports in opposite directions.

26. In a mining machine, a frame having adjustable front and rear supports, a machine body mounted on said frame for rotation about an axis extending longitudinally of the machine, cutting mechanism carried by said body, a motor carried by said body, and mechanism driven by said motor for adjusting said front support independently of said rear support.

27. In a mining machine, a frame having adjustable front and rear supports, a machine body mounted on said frame for rotation about an axis extending longitudinally of the machine, cutting mechanism carried by said body, a motor carried by said body, and mechanism driven by said motor for independently adjusting said supports.

28. In a mining machine, a frame having adjustable front and rear supports, a machine body mounted on said frame for rotation about an axis extending longitudinally of the machine, cutting mechanism carried by said body, a motor carried by said body, and mechanism driven by said motor for independently or simultaneously adjusting said supports.

29. In a mining machine, a frame having adjustable front and rear supports, a machine body mounted on said frame for rotation about an axis extending longitudinally of the machine, cutting mechanism carried by said body, and mechanism for simultaneously or

independently adjusting said supports to vary the elevation and angle in altitude of said body.

30. In a mining machine, a frame having adjustable front and rear supports, a machine body mounted on said frame for rotation about an axis extending longitudinally of the machine, cutting mechanism carried by said body, a motor carried by said body, and mechanism driven by said motor for independently adjusting said supports to vary the angle in altitude of said body.

31. In a mining machine, a frame having adjustable front and rear supports, a machine body mounted on said frame for rotation about an axis extending longitudinally of the machine, cutting mechanism carried by said body, a motor carried by said body, and mechanism driven by said motor for independently or simultaneously adjusting said supports to vary the angle in altitude and elevation of said body.

32. In a mining machine, a frame having adjustable front and rear supports, a machine body mounted on said frame for rotation about an axis extending longitudinally of the machine, mechanism driven by said motor for effecting rotation of said body relative to said frame, cutting mechanism carried by said body, a motor carried by said body, and mechanism driven by said motor for adjusting said front support independently of said rear support.

33. In a mining machine, a frame having adjustable front and rear supports, a machine body mounted on said frame for rotation about an axis extending longitudinally of the machine, mechanism driven by said motor for effecting rotation of said body relative to said frame, cutting mechanism carried by said body, a motor carried by said body, and mechanism driven by said motor for independently adjusting said supports.

34. In a mining machine, a frame having adjustable front and rear supports, a machine body mounted on said frame for rotation about an axis extending longitudinally of the machine, mechanism driven by said motor for effecting rotation of said body relative to said frame, cutting mechanism carried by said body, a motor carried by said body, and mechanism driven by said motor for independently or simultaneously adjusting said supports.

35. In a mining machine, a frame having adjustable front and rear supports, a machine body mounted on said frame for rotation about an axis extending longitudinally of the machine, mechanism driven by said motor for effecting rotation of said body relative to said frame, cutting mechanism carried by said body, and mechanism for simultaneously or independently adjusting said supports to vary the elevation and angle of said body.

36. In a mining machine, a frame having adjustable front and rear supports, a machine body mounted on said frame for rotation about an axis extending longitudinally of the machine, mechanism driven by said motor for effecting rotation of said body relative to said frame, cutting mechanism carried by said body, a motor carried by said body, and mechanism driven by said motor for independently adjusting said supports to vary the angle in altitude of said body.

37. In a mining machine, a frame having adjustable front and rear supports, a machine body mounted on said frame for rotation about an axis extending longitudinally of the machine, mechanism driven by said motor for effecting rotation of said body relative to said frame, cutting mechanism carried by said body, a motor carried by said body, and mechanism driven by said motor for independently or simultaneously adjusting said supports to vary the angle in altitude and elevation of said body.

38. In a mining machine, a machine body, supporting means for said body comprising front and rear pivoted wheel carrying supporting arms, cutting mechanism carried by said body and swingable through an arc of substantially 180° irrespective of the positions of said arms, a motor carried by said body, and mechanism driven by said motor for adjusting said front pivoted arm independently of said rear pivoted arm.

39. In a mining machine, a machine body, cutting mechanism carried thereby, a motor carried by said body, supporting means for said body comprising pivoted front and rear wheel carrying supporting arms, and mechanism driven by said motor for independently adjusting said arms about their pivots, said cutting mechanism having a mounting on said body permitting swinging through substantially a semicircle irrespective of the positions of said arms.

40. In a mining machine, a machine body, cutting mechanism carried thereby, a motor carried by said body, supporting means for said body comprising pivoted front and rear wheel carrying supporting arms, and mechanism driven by said motor for independently or simultaneously adjusting said arms about their pivots, said cutting mechanism having a mounting on said body permitting swinging through substantially a semicircle irrespective of the positions of said arms.

41. In a mining machine, a machine body, cutting mechanism carried thereby, supporting means for said body comprising pivoted front and rear wheel carrying supporting arms, and mechanism interconnecting said arms for simultaneously or independently adjusting said arms about their pivots, said cutting mechanism having a mounting on said body permitting swinging through sub-

stantially a semicircle irrespective of the positions of said arms.

42. In a mining machine, a machine body, cutting mechanism carried thereby, supporting means for said body comprising pivoted front and rear wheel carrying supporting arms, a motor carried by said body, and mechanism driven by said motor for independently adjusting said arms about their pivots to vary the angle in altitude of said body, said cutting mechanism having a mounting on said body permitting swinging through substantially a semicircle irrespective of the positions of said arms.

43. In a mining machine, a machine body, cutting mechanism carried thereby, supporting means for said body comprising pivoted front and rear wheel carrying supporting arms, a motor carried by body, and mechanism driven by said motor for independently or simultaneously adjusting said arms about their pivots to vary the angle in altitude and elevation of said body, said cutting mechanism having a mounting on said body permitting swinging through substantially a semicircle irrespective of the positions of said arms.

44. In a mining machine, a machine body, cutting mechanism carried thereby, a motor in said body, adjustable front and rear supports for said body, and mechanism driven by said motor for adjusting said supports including a differential having corresponding elements operatively connected to said supports and through which power transmitted to said supports is automatically equally proportioned.

45. In a mining machine, a machine body, cutting mechanism carried thereby, a motor in said body, adjustable front and rear supports for said body, and mechanism driven by said motor for adjusting said supports including a differential having corresponding elements operatively connected to said supports and through which power transmitted to said supports is automatically equally proportioned, and means for resisting movement of the adjusting means for one support to effect a corresponding increase in the rate of adjustment of the other support.

46. In a mining machine, a machine body, cutting mechanism carried thereby, a motor in said body, adjustable front and rear supports for said body, and mechanism driven by said motor for adjusting said supports including a differential having corresponding elements operatively connected to said supports and through which power transmitted to said supports is automatically inversely proportioned.

47. In a mining machine, a machine body, cutting mechanism carried thereby, a motor in said body, adjustable front and rear supports for said body, and mechanism driven by said motor for adjusting said supports in-

cluding a differential having corresponding elements operatively connected to said supports and through which power transmitted to said supports is automatically inversely proportioned, and frictional devices controlling different elements of said differential.

48. In a mining machine, a machine body, cutting mechanism carried thereby, and mounted for swinging movement on an axis adjacent one end of said body, a motor carried by said body, adjustable front and rear supports for said body each including support wheels adapted to run along a mine trackway, and mechanism driven by said motor for independently adjusting said supports to effect movement of said support wheels relative to each other to vary the angle in altitude of said cutter carrying body.

49. In a mining machine, a machine body, cutting mechanism carried thereby and mounted for swinging movement on an axis adjacent one end of said body, a motor carried by said body, adjustable front and rear supports for said body each including support wheels adapted to run along a mine trackway, and mechanism driven by said motor for independently or simultaneously adjusting said supports to effect movement of said support wheels relative to each other to vary the elevation and angle in altitude of said cutter carrying body.

50. In a mining machine, a machine body, cutting mechanism carried thereby, and mounted for swinging movement on an axis adjacent one end of said body, adjustable front and rear supports for said body each including support wheels adapted to run along a mine trackway, and mechanism for simultaneously or independently adjusting said supports to effect movement of said support wheels relative to each other to vary the elevation and angle in altitude of said cutter carrying body.

51. In a mining machine, kerf cutting mechanism, mounted for positioning to cut in substantially horizontal or in substantially vertical planes and adjustable supporting means for said cutting mechanism including adjustable front and rear supports, and mechanism for adjusting said supports including a power operated element and adjusting devices for each support including a clutch for connecting said adjusting devices to said power operated element.

52. In a mining machine, kerf cutting mechanism, and adjustable supporting means for said cutting mechanism including adjustable front and rear supports, said cutting mechanism being swingable about an axis in advance of said front support and power operated mechanism for adjusting said supports including adjusting connections arranged at opposite sides and extending longitudinally of the machine.

53. In a mining machine, kerf cutting

mechanism, and adjustable supporting means for said cutting mechanism including adjustable front and rear supports, said cutting mechanism being swingable about an axis in advance of said front support and mechanism for independently adjusting said supports including a power operated element and speed varying mechanism driven thereby.

5 54. In a mining machine, kerf cutting mechanism, adjustable supporting means for said cutting mechanism including adjustable front and rear supports, said cutting mechanism being swingable about an axis in advance of said front support mechanism for independently adjusting said supports including a power operated element and speed varying mechanism driven thereby, and propelling means for the machine driven through said speed varying mechanism.

10 55. In a mining machine, kerf cutting mechanism, adjustable supporting means for said cutting mechanism including adjustable front and rear wheeled supports, said kerf cutting mechanism being swingable about an axis in advance of said front support, motor operated devices for independently adjusting said supports including a differential, and mechanism driven through said differential for driving the support wheels to propel the

15 56. In a mining machine, a machine body, cutting mechanism carried thereby, a motor in said body, adjustable front and rear supports for said body, said kerf cutting mechanism being swingable about an axis in advance of said front support, mechanism driven by said motor for independently adjusting said supports including an orbitally movable element through which power is transmitted to effect adjustment of both supports, and mechanism driven through said orbitally movable element for propelling the machine.

20 In testimony whereof I affix my signature.
45 CORNELIUS G. BOUDETTE.
